BED HEATER

Walter J. Miller, South Bend, Ind.

Application December 4, 1947, Serial No. 789,603

14 Claims. (Cl. 219—38)

1

This invention relates to improvements in bed heaters, and particularly to heaters usable by persons confined to bed with tuberculosis or pulmonary diseases requiring fresh air treatment. During cold weather such bedridden persons must use some type of a heater to provide an external source of heat to prevent discomfort and objectionable chilling of the body. To be fully satisfactory a heater of this character must possess various properties. Thus its shape and size must be such as to permit it to be positioned near different parts of the body of the patient. It must provide protection against overheating or burning of either the patient or the bed clothing, and it must provide for circulation of air therearound.

The primary object of this invention is to provide a device which serves the purpose and satisfies the requirements mentioned above.

A further object is to provide a device of this character with a frame formed from insulating material and constructed for free circulation of air between the outer portion thereof and a heat-generating portion positioned interiorly thereof.

A further object is to provide a device of this character with a cage within which is positioned a housing adapted to receive a heat-generating element, said element being removably mounted and supported in fully insulated relation to the cage, and the housing being spaced inwardly from the grill or open portions of the cage.

A further object is to provide a device of this character with novel humidifying means.

A further object is to provide a device adapted to be placed in a plurality of angularly related positions and including a heating chamber with a plurality of openings, each provided with a pivoted closure member, wherein said closure members are so constructed and positioned that one thereof will open automatically to provide for air circulation in the heating chamber in each of the positions in which the device may be placed.

A further object is to provide a device of this character with triangular end members which are interconnected by spaced bars or grills and which support therebetween a heating chamber spaced inwardly from said bars and removably receiving a heating element, wherein all exposed or external parts of the device are formed of insulating material.

A further object of the invention is to provide a device of this character which is simple in construction, easy to assemble and disassemble for repair and adjustment, inexpensive, light in weight, and which may be used safely in contact with bed clothing and the body of a patient.

2

Other objects will be apparent from the following specification.

In the drawing:

Fig. 1 is a view of the device in side elevation.

Fig. 2 is an end view of the device looking toward the right in Fig. 1.

Fig. 3 is a longitudinal vertical sectional view taken on line 3—3 of Fig. 2.

Fig. 4 is a transverse vertical sectional view taken on line 4—4 of Fig. 1.

Fig. 5 is a transverse sectional view of a humidifying attachment.

Fig. 6 is an enlarged sectional detail view of a portion of the humidifying attachment.

Referring to the drawings which illustrate the preferred embodiment of the invention, the numeral 10 designates two similar end frame members which are preferably of triangular form and are provided with central triangular openings 12 of substantially the same shape as the outer triangular shape of the frame members. As best seen in Fig. 2, the frame members 10 are of a shape in which the three sides thereof are of different lengths so that the two upstanding sides thereof in each of its three possible positions resting upon a third side will extend at different angles relative to the vertical. The points or corners of the frame members are preferably rounded at 14, and the edges of the frame members are also preferably rounded so that no sharp edges occur. The members 10 are preferably formed of wood although they may be formed of other insulating material such as a thermosetting plastic. The primary requirement of the material of which the members 10 are formed is that the same provide good insulation against both heat and electricity. In other words, the material of which members 10 is formed should be a dielectric material and it should possess a high resistance to the transfer of heat therethrough.

The two end members 10 are rigidly interconnected by a plurality of rods or bars 16, each fixedly secured or anchored at its opposite ends to the frame members 10. The bars or rods at the corners may be larger than the remaining bars and each thereof should be of substantial strength and formed of wood, thermosetting plastic material or other material which preferably has the same properties of insulation against heat transfer and against electric current as described with respect to frame members 10. The bars or rods 16 are preferably arranged in parallel relation perpendicular to the frame members 10 and spaced apart substantially uniformly. The preferred spacing of the bars or rods preferably does

not exceed three-fourths of an inch, although this spacing is optional. The device is made of such a size that a plurality of bars, as best illustrated in Fig. 4, span the two end members 10 adjacent each of the edges thereof. The rods 16 are preferably spaced inwardly slightly from the edges of the frame members 10 and are spaced from the inner edges 12 of said frame members a greater distance, as best seen in Fig. 4.

A tubular member 18 is mounted at its opposite ends within the openings 12 of the end members to span the same and define an open ended heating chamber. The member 18 is preferably formed of sheet metal, is secured to the end members 10 in any suitable manner, and is of a cross-sectional shape conforming to the shape of the openings 12. As here illustrated, the chamber 18 is of triangular cross-section with its side walls substantially parallel to and equispaced from the marginal edges of the frame members 10 and the bars 16. One end of the chamber 18 is spanned by a closure panel 20 provided with a plurality of apertures 22 formed therein to register with the interior of the casing member 18. The closure 20 is formed of a nonconducting material, such as wood, thermoplastic material or composition material of the character commonly known as hardboard. The panel 20 preferably bears against spacers 24 which engage the outer faces of one of the end members 10 and is secured to the end member by securing members 26. Thus the end of the device provides a plurality of paths for air circulation into and out of the heat chamber 18, the same constituting the openings 22 in the panel 20 and the space, best illustrated in Figs. 1 and 3, which separates the panel 20 from the adjacent end member. Additional openings for passage of air into and out of the chamber 18 may be provided in spaced relation to the end panel 20. As here illustrated, the tubular chamber member 18 may be provided with a plurality of openings 28 in its side walls which are of substantially the same size as the openings 22 in the panel 20, and each side wall of the panel may be further provided with a comparatively large opening 30 positioned substantially centrally of the length of the member 18. The openings 30 are preferably of the shape best illustrated in Fig. 4 providing a large primary opening from which a reduced portion projects longitudinally. This reduced portion may be defined in part of the space provided by bending a portion of the material of the member 18 to define an integral outwardly projecting cylindrical part 32, as best shown in Fig. 3, which defines a hinge socket. A sheet metal closure plate 34 spans each aperture 30, bearing at its margin upon the surface of the wall of the chamber 18 around the opening 30 and being provided with a tongue which fits rotatably within the cylindrical socket 32 and provides a pivot axis or hinge pintle to which the plate 34 may be pivoted. It will be understood that the shape of the opening and the shape and hinge construction of the pivoted closure, as herein defined, is illustrative only and that any other shape and construction of these parts which will permit the pivotal mounting of a closure to span the opening at the outer surface of the tubular member 18 which is found suitable, may be employed in the device. It will be observed from Figs. 1 and 3 that the construction is such that the closures 34 will be positioned by gravity. Consequently the lowermost opening 30 will be opened by the pivotal opening of the associated closure 34 by gravity, and the remaining

openings 30 will be closed because of the upward and inward inclination of the wall portions in which said openings are formed, which provides for the action of gravity upon the closure 34 of said openings in a direction to close the same. This permits the intake of air into the chamber within the tubular member 18 from its bottom, and the remaining openings, such as the openings 22, 28 and the space between the members 10 and 20 provide air outlets, thus permitting the circulation of air surrounding the heater by convection flow. It will be apparent that the triangular shape of the device, when made in an effective size entailing a height in the Fig. 2 position of approximately 6 to 10 inches, will hold the bed covering or blankets spaced above the mattress to provide an air space in which the circulation can occur. Furthermore, it will be apparent that, even in cases where the bed covers are fitted closely around the device, the space between the bars 16 and the heat chamber will provide an air circulating space.

The end of the tubular member 18 opposite that spanned by the plate 20 is spanned and closed by a panel 36 which is formed of a dielectric material having heat insulating properties, such as wood, thermosetting plastic material or composition board. The panel 36 is secured to the frame member 10 by the securing members 38, such as wood screws, and, if desired, may be spaced from the member 10 by the use of spacers in the same manner in which panel 20 is spaced from the end member 10. The panel 36 is preferably strong and rigid and is adapted to provide a support for a carrier which mounts an electrical heating element and other electrical parts used in conjunction with a heating element. In the form illustrated, the carrier comprises a rigid U-shaped bracket which may be formed of metal or any other suitable material having an arm 40 which is clamped against the panel 36 by a rigid panel 42 which may be formed of some dielectric material, such as composition board or hardboard. The panel 42 is held in clamped relation to the panel 36 by suitable securing means, such as bolts and nuts 44. The base 46 of the U-shaped carrier is so positioned that it is spaced from and clear of the metal tubular sheath 18 in its operative position, as best shown in Fig. 3. This base preferably mounts a block 48 of an electric insulating material, such as asbestos, rubber, thermosetting plastic material, or the like. A pilot heating element 50 is supported upon the block 48 and secured in operative position thereto by a retainer, such as a band 52 passing around the base 46 and the element 50. The inner leg 54 of the carrier preferably extends substantially parallel to the leg 40 in spaced relation thereto, and a block 56 of insulating material bears against one face thereof. A second block of insulating material 58 is positioned parallel to the block 56 and is backed by the rigid housing of a thermostat 60. Securing members 62, such as bolts and nuts, serve to clamp the thermostat and the leg 54 in position to grip between the blocks 56 and 58 an electrical heating element 64 of any suitable type and construction. As here illustrated in Fig. 4, this heating element comprises a flat annular member formed of electrical resistance material adapted to generate heat when current is passed therethrough. Suitable electrical connections (not shown) are effected between the terminals 66 of the thermostat 60 and the heating element. Electrical leads 68 connect the terminals 66 with terminals 70 carried by the panel 42, and a three-wire electrical

cord 72 has its wires connected to the terminals 70 and the terminals of the element 50 in circuit controlling relation, as well understood in the art. The electrical cord 72 is preferably an elongated flexible sheathed and insulated cord which passes through an opening in the panel 36 and through a lead-in socket of conventional construction carried by the outer surface of the panel 36 and serving the purpose of preventing kinking of and damage to the electrical cord. As here shown, this socket is formed of rubber or other flexible insulating material and has an enlarged base flange 74 of a size to overlie the securing members 44, the terminal 70 and other parts anchored to the panel 36, and has a tubular extension 76 through which the cord 72 extends and by which the cord is positioned. The cord will be provided with a suitable selector switch (not shown) intermediate its length which may be positioned within the reach of the patient in all positions of the heater to permit the patient to energize or deenergize the heating elements 50 and 64 and which may further include plural settings for selectively controlling the circuits to the individual heating elements. Selector switches of this type are commonly known in the art and do not form a part of this invention, and for this reason have not been illustrated herein.

It will be observed that the construction and arrangement of the electrical parts and their mounting upon a common support, namely the panel 36, facilitates the assembly and disassembly of the device and makes possible the removal of the heating element by disconnecting the panel 36 from the remainder of the device. The construction is such that all of the electrical parts are held in fixed relation to each other and to the panel 36 so that all danger of short circuit is avoided and yet full access for repair and replacement of parts is afforded.

By reason of the shape of the device, as best illustrated in Fig. 2, wherein the sides of the triangle are of different lengths and at different angles, it is possible to position the heater closely adjacent to any part of the body without discomfort to the user. The formation of the outer cage of the device, constituting the end members 10, the panels 36 and the bars 16, from dielectric material having a low heat conductivity permits the device to be positioned directly in contact with the body of the patient without danger of injury due either to electrical shock or to excess heat. Thus it is possible to place the heater for engagement of the feet of the patient therewith, place it against the side or back of the patient, or in any other position where the source of heat is desired. The device can be positioned at any angle selected so that comfort is assured, for instance, at such an angle that the soles of the feet may press comfortably against the bars 16 without requiring the feet to be held in an uncomfortable position. Air circulation and the transfer of heat under the bed covering around the body of the patient is assured by the convection flow of air to and through the heater, the cage insuring that the bed covers will not close the air passages communicating with the heating chamber. In this connection, the air will always be drawn into the heating chamber through the bottom by virtue of the automatic opening by gravity of the closure 34 which is positioned lowermost in the device. These features and other advantages of the device render it particularly satisfactory for its intended use by bedridden patients, render it safe for such use, and permit its use with comfort.

The use of a bed heater of this particular type over any substantial period of time will cause the air being heated thereby to be dried, thereby lowering the humidity of the air around the patient's body. This has an adverse effect upon the skin, tending to dry out the skin and cause discomfort. For this reason it may be desirable in most instances to provide humidifying means within the device, particularly where the device is used by bedridden individuals.

Such humidifier has been illustrated in Figs. 3, 5 and 6 and includes a pair of end members 80 of a size and shape to fit snugly and slidably within the tubular portion 18 of the heater. These end members are rigid and are connected together by longitudinal bars or rods 82 and are spanned by a tubular absorbent member 84. The end members 80 have central openings 86 therein, defined in part by integral cylindrical wall portions 88 around which the opposite ends of the absorbent tubular part 84 fit. An outer circular rib or flange 90 concentric with the cylindrical flange 88 fits around the outer ends of the absorbent member 84. The construction is rigid and may easily be inserted into and removed from the tubular part 18 of the device. In cases where the humidifier is utilized, the end panel 20 may be omitted if desired, particularly if means are provided for positioning the humidifier in the device. Such means may comprise spring clips 92 adapted to engage and hold the outermost panel 80 detachably in selected position.

The absorbent tubular member 84 may be of any suitable construction, it being desirable, however, that such member will not lose its contained moisture by a dripping action. Thus, if desired, a porous refractory member may be employed. Such refractory members have limited water-absorbing capacity, and I prefer to employ a construction of the character best illustrated in Fig. 6, wherein a thin flexible corrugated metal sheet 94 has adhered thereto an absorbent fibrous sheet member 93, such as a sheet of asbestos material. This built up sheet, comprising the non-corrosive flexible metal backing and the absorbent fibrous sheet 94, may be rolled into tube form providing a plurality of laminations, as illustrated in Fig. 6. The arrangement is preferably such that the metal sheet 94 will be positioned outermost and the absorbent sheet 93 will be positioned innermost and will be encircled by a tube 95 cemented at its ends to the flanges 90. A device of this character, where the end members are formed of material such as a plastic or non-corrosive metal, may be immersed in a body of water to absorb an amount of liquid therein up to the level of the line 96 in Fig. 5. This will be adequate to provide saturation by an amount of water which will supply the desired humidity for a substantial period of time. The amount of water absorbed should not be greater than that which is retained by one of the cylindrical flanges 88 when the humidifier is positioned on end. In this connection it will be apparent that air entering the device from the end will pass through the tubular absorbent member 84 to pick up the moisture of the wetted inwardly facing porous lamination 93 for the desired amount of moisture transfer to the air.

This humidifying device is an attachment whose use is optional and which avoids all disadvantages and hinderances to the use of humidifiers. Thus the enclosure of the humidifier within the device prevents the possibility that the bed clothing will be wetted by the humidifier, the construction of the absorbing agent avoiding

all danger of dripping of water from the humidifier. Likewise, no danger of electrical shock is entailed despite the use of an electrical heating element in the presence of a humidifier because the manufacture of the end plates 80 of the humidifier from a plastic, such as a thermosetting phenolic plastic, will avoid all danger of transmission of electrical shock to the user or to the sheath 18.

While the preferred embodiment of the invention has been described and illustrated herein, it will be understood that changes may be made in the construction within the scope of the appended claims without departing from the spirit of the invention.

I claim:

1. A bed heater comprising a pair of similar end members, each having a plurality of angularly disposed flat end portions, a plurality of spaced bars connecting the marginal portions of said end members, an open ended tubular member spanning and secured to said end members in inwardly spaced relation to said bars, a pair of closures carried by said end members and spanning the ends of said tubular member, said tubular member and at least one closure having passages for air circulation through said tubular member in one or more laterally discharging predetermined paths, and an electrical heating element carried by one closure and positioned within said tubular member.

2. A bed heater comprising a pair of similar end members, each having a plurality of angularly disposed flat edge portions, a plurality of spaced bars connecting the marginal portions of said end members, an open ended tubular member spanning and secured to said end members in inwardly spaced relation to said bars, a pair of closures carried by said end members and spanning the ends of said tubular member, said tubular member having apertures therein at portions substantially centrally located relative to the planes defined by said flat edge portions, and an electrical heating element carried by one closure and positioned within said tubular member, said end members, bars and closures being formed of a dielectric material having a low heat conductivity.

3. A bed heater comprising a pair of similar end members, each having a plurality of angularly disposed flat edge portions, a plurality of spaced bars connecting the marginal portions of said end members, an open ended tubular member spanning and secured to said end members in inwardly spaced relation to said bars, a pair of closures carried by said end members and spanning the ends of said tubular member, at least one of said closures being spaced from the end member which mounts it and from said tubular member, and an electrical heating element carried by one closure and positioned within said tubular member, said tubular member being of a cross-sectional shape substantially similar to the shape of said end members and having substantially flat portions provided with apertures therein substantially centrally located between the longitudinal edges defining said flat portions, each of said bars being spaced from said tubular member substantially the same distance.

4. A bed heater comprising a pair of similar end members, each having a plurality of angularly disposed flat edge portions, a plurality of spaced bars connecting the marginal portions of said end members, an open ended tubular member spanning and secured to said end mem-

bers in inwardly spaced relation to said bars, a pair of closures carried by said end members and spanning the ends of said tubular member, and an electrical heating element carried by one closure and positioned within said tubular member, said tubular member and at least one closure each having an aperture therein for the passage of air into and out of said tubular member, the apertures in said tubular member being located spaced below the uppermost portion thereof in all positions of said heater.

5. A bed heater comprising a pair of similar end members, each having a plurality of angularly disposed flat edge portions, a plurality of spaced bars connecting the marginal portions of said end members, an open ended tubular member spanning and secured to said end members in inwardly spaced relation to said bars, a pair of closures carried by said end members and spanning the ends of said tubular member, and an electrical heating element carried by one closure and positioned within said tubular member, said tubular member having a plurality of openings therein each in a portion thereof adjacent to a flat edge of said end members, and a closure adapted to span each opening and hinged to said tubular member to pivot to open position when the adjacent flat edge of said end members bears on a support.

6. A bed heater comprising a pair of similar end members, each having a plurality of angularly disposed flat edge portions, a plurality of spaced bars connecting the marginal portions of said end members, an open ended tubular member spanning and secured to said end members in inwardly spaced relation to said bars, a pair of closures carried by said end members and spanning the ends of said tubular member, and an electrical heating element carried by one closure and positioned within said tubular member, said end member being of triangular form with the edges thereof of different lengths and positioned in acute angled relation.

7. A bed heater comprising a pair of similar end members, each having a plurality of angularly disposed flat edge portions, a plurality of spaced bars connecting the marginal portions of said end members, an open ended tubular member spanning and secured to said end members in inwardly spaced relation to said bars, a pair of closures carried by said end members and spanning the ends of said tubular member, and an electrical heating element carried by one closure and positioned within said tubular member, the closure opposite that which mounts said heating element being apertured and being mounted in outwardly spaced relation to the adjacent end member, said tubular member having apertures therein spaced from said last named aperture and spaced below the uppermost part of the tubular member in all positions of the heater.

8. A heater comprising a cage structure defined by end members and bars interconnecting said end members, a housing supported within said cage and spaced inwardly relative to said bars, a heating element enclosed within said housing, said cage having a plurality of angularly disposed supporting surfaces, said housing having a plurality of apertures, and closures pivoted to said housing adjacent selected apertures, one closure being located adjacent each supporting surface, the lowermost closure being adapted to swing to open position by gravity.

9. A heater comprising a cage structure of triangular shape in cross-section and having grilles

sides and end closures, a housing carried by said structure spaced inwardly relative to the grilled sides thereof, said housing defining a heating chamber and having air circulating apertures in each side and at least one end thereof, a heating element within said chamber, and closures pivoted to said housing and each adapted to span one of said side apertures and to swing by gravity to open position when positioned lowermost.

10. A heater comprising a cage structure of triangular shape in cross-section and having grilled sides and end closures, a housing carried by said structure spaced inwardly relative to the grilled sides thereof, said housing defining a heating chamber and having air circulating apertures in each side and at least one end thereof, a heating element within said chamber, and closures pivoted to said housing and each adapted to span one of said side apertures and to swing by gravity to open position when positioned lowermost, said heating element being an electrical resistance element, said cage having a removable end member, and means carried by said removable end member for mounting said heating element.

11. A bed heater adapted to be positioned beneath the covers of a bed comprising a cage structure defined by end members and bars interconnecting said end members, a housing carried by said end members in inwardly spaced relation to said bars, a heating element enclosed within said housing, said end members and housing having air circulating apertures therein, and a humidifier detachably mounted in said housing.

12. A bed heater adapted to be positioned beneath the covers of a bed comprising a cage structure defined by end members and bars interconnecting said end members, a housing carried by said end members in inwardly spaced relation to said bars, a heating element enclosed within said housing, said end members and housing having air circulating apertures therein, and a humidifier detachably mounted in said housing, said humidifier comprising a pair of spaced apertured end panels, and a porous tubular member carried by said panels with its bore communicating with said panel apertures.

13. A bed heater adapted to be positioned be-

- neath the covers of a bed comprising a cage structure defined by end members and bars interconnecting said end members, a housing carried by said end members in inwardly spaced relation to said bars, a heating element enclosed within said housing, said end members and housing having air circulating apertures therein, and a humidifier detachably mounted in said housing, said humidifier comprising a pair of spaced apertured end panels, and a porous tubular member carried by said panels with its bore communicating with said panel apertures, and a spring retainer carried by said housing and engageable with an end panel.
14. A heater comprising a cage structure defined by end members and bars interconnecting said end members, a housing carried by said end members in inwardly spaced relation to said bars, a heating element enclosed within said housing, said end members and housing having air circulating apertures therein, and a humidifier detachably mounted in said housing, said humidifier comprising a pair of spaced apertured end panels, and a porous tubular member carried by said panels with its bore communicating with said panel apertures, said end panels each having an annular flange around the aperture thereof, and said porous member comprising a plurality of convolutions of a laminated structure, each lamination including a corrugated sheet of metal and an absorbent fibrous sheet adhered to the inner face of said metal sheet.
